UNITED STATES PATENT OFFICE

2,242,229

ABRADING DEVICE

Arthur C. Burleigh, Wellesley, Mass., assignor to
 Skilsaw Inc., Chicago, Ill., a corporation of
 Delaware

Application December 26, 1939, Serial No. 310,934

9 Claims. (Cl. 51—170)

This invention relates to abrading devices and has for its object to provide a new and improved device of this description.

The invention has as a further object to provide an abrading device which shall be small, easily lifted and controlled, and which can be used among other things, to smooth the surface of the floor in proximity to the baseboard without injury to the baseboard. The invention has as a further object to provide a relatively small abrading device with handles appropriately placed, for moving it, the device being provided with an abrading disc with a motor for operating it and a fan with a separate motor for operating it and a removable casing which encloses the motors for the abrading disc and the fan.

The invention has further objects which are more particularly pointed out in the accompanying description.

Referring now to the drawings, Fig. 1 is a plan view of one form of device embodying the invention;

Fig. 2 is a side elevation of the device shown in Fig. 1;

Fig. 3 is a vertical sectional view taken on line 3—3 of Fig. 1;

Fig. 4 is a bottom view;

Fig. 5 is a sectional view taken on line 5—5 of Fig. 3;

Fig. 6 is a front elevation of the device shown in Fig. 1;

Fig. 7 is a detail showing a modified construction for the part which engages the baseboard.

Like numerals refer to like parts throughout the several figures.

Referring now to the drawings, in the particular construction shown the supporting structure for the parts is divided into two sections 1 and 2, which are removably connected together in any desired manner, as by means of the fastening devices 3. The section 1 contains the rotary abrading disc 4 which has its face covered with abrading material 5, which may be a sheet of sand paper or any other abrading material. There is a pad of felt or other material 6 between the abrading sheet 5 and the disc proper 4. The abrading disc 4, the pad 6 and the abrading paper or cloth 5 are all centrally apertured. There is a central holding member 7 which is a disc preferably having a flat bottom and an inclined top and which is preferably provided with a hub 8 which projects up through the central apertures in the abrading disc, pad and abrading sheet, as clearly shown in Fig. 3. This hub is hollow and internally screwthreaded and the

driving shaft 9 for the abrading disc has its end screwthreaded, and threaded into this threaded opening in the hub 8.

The top of the abrading disc 4 is preferably flat and there is a disc 10 on top of it which has a central aperture through which the driving shaft 9 passes. This disc is fastened to the abrading disc 4 by the fastening devices 11 which preferably have their ends extending into metal inserts 12 in the abrading disc 4. The driving shaft 9 is connected with the abrading disc 4 so as to rotate this disc when the driving shaft is rotated. There is an annulus 9a extending around the driving shaft 9 which is integral with the disc 10. A key 9b connects the driving shaft 9 and the disc 10, which in turn is connected with the abrading disc 4 so that the shaft rotates this disc.

The section 1 is provided with an engaging part 13 which preferably projects slightly beyond the periphery of the abrading disc so as that it engages the baseboard, wash board, or any other vertical member, so that when the disc is used to smooth up the edges of the floor or other surface, this engaging part 13 will engage the baseboard, wash board or the like, and prevent the abrading disc from engaging it so as to injure or mar it. This engaging part 13 is rigid with the section 1 of the supporting structure and is preferably integral therewith. Its lower edge may be a short distance above the abrading disc, as shown, for example in Fig. 3, or it may be provided with a thin edge 14 which projects down part way across the abrading disc 4, as shown in Fig. 7.

The driving shaft 9 extends upwardly through an opening in the top of the section 1, which acts as a bearing for it and is preferably provided with ball bearing 15 which rests on a shoulder 15a on the upper wall of section 1. The driving shaft 9 has connected therewith a gear 16 which engages a pinion 17 fastened to the motor shaft 18 so as to rotate therewith. The upper wall 19 of the section 2 of the supporting structure is provided with a recess 19a in which is located a bearing 20 for the upper end of the driving shaft 9, which bearing is preferably a ball bearing. This recess may be formed in any desired manner, as, for example, by providing the wall with the downwardly projecting annulus 21. The upper wall 19 of the section 2 is also recessed at 22 to receive the bearing 23 for the motor shaft, which is preferably a ball bearing. This recess may be provided in any desired manner, as, for example, by means of the downwardly projecting annulus 24 on the upper wall 19. The two re-

cesses as herein shown have a common wall 25 which permits the motor shaft 18 and the driving shaft 8 to be brought very close together.

The motor shaft 18 is connected with a motor which is located in a motor housing 26 which is open at the top and which has a member 27 extending across the top, which contains a ball bearing for the upper end of the motor shaft 18. The housing 26 is removably connected with the section 2. Connected with the motor shaft 18 is a fan 28 which moves air through the motor housing for ventilating and cooling purposes. Mounted upon the motor housing 26 is a lamp 29 which is connected in circuit by the conductors 30. The section 2 is provided with the separated upstanding members 31 and the motor housing is provided at the corners with the projections 32 which rest upon the upstanding members 31. The motor housing is connected to the section 2 by the removable fastening devices 33 which extend through the projections 32 and into the upstanding members 31.

Mounted within a chamber 34 is a fan 35 which is connected with the shaft 36 of a motor mounted in the motor housing 37, removably attached to the section 2 by the removable fastening devices 38. The fan chamber 34 is provided with a discharge opening 39 which is connected to a collector 40 which may be of any suitable type now used. This fan chamber 34 is also provided with an inlet opening 41 which connects with the chamber 42 in the section 1. This chamber 42 has an inlet opening 43 in proximity to the abrading disc, so that when the device is in operation the material removed by the abrading disc passes up through the inlet 43 into the chamber 42 and thence through the inlet 41 into the chamber 34 and thence into the collector 40. The section 1 as herein shown is provided with a material receiving groove 44 which is formed with a downwardly projecting outer wall 45 and a downwardly projecting inner wall 46. There is an admission opening 47 through which the material removed by the abrading disc is drawn into the groove 44 and thence up through the inlet 43. There is preferably provided a flexible strip 48 which is attached to the section 1 and which extends from the opening 47 part-way along the wall 45, see Fig. 4. This flexible strip projects downwardly beyond the lower edge of the wall 45 and its lower edge is preferably slit to form a series of separated members. The purpose of this device is to direct the material removed by the abrading disc toward the fan.

There is a removable cover 49 which fits over the motor housings 26 and 37 and which is fastened to the section 2. This cover may be fastened in position in any desired manner. As herein shown, there are recesses 50 and 51 in the sides thereof. Fastening devices 52 and 53 fasten the cover to the section 2, the heads of the fastening devices being recessed in the recesses 50 and 51, see Figs. 2 and 6. The cover is provided with an opening 54 through which the lamp 29 shines. There is a switch 55 connected with the cover 49, with which the circuits for the electric motors in the housings 26 and 37 are connected. This switch is provided with a threaded member 56 which is received in an opening in the casing. The actuating member 57 for the switch projects through the member 56 so as to be accessible from the outside of the cover. There is also a separate switch 58 for the fan motor in the motor housing 37. The

cover 49 is provided with two handles 59, 60 by means of which the device is manipulated.

It will be noted that the section 1 is largest at the point where the abrading disc is located and that it narrows down back of the disc to a size approximating that of the inlet 41 of the section 2. Section 2 is preferably elliptical in shape and is considerably narrower at the front than the section 1, the section 1 projecting beyond the section 2 at the sides and at the front, see Fig. 1. Section 2 is provided at its sides intermediate its front and rear ends, with the laterally projecting parts 61 and 62. Connected with these laterally projecting parts are the caster wheels 63 and 64 which are mounted in the members 65 and 66, which are rotatably connected with the threaded members 67 and 68 which pass through threaded openings in the laterally projecting parts 61 and 62. Lock nuts 69 and 70, when tightened up, lock the parts 67 and 68 in position. It will be noted that the members 65 and 66 with which the caster wheels are connected are free to move at all times with relation to the sections 1 and 2 and that these caster wheels may be adjusted up or down by loosening the lock nuts and rotating the members 67 and 68 in one direction or the other. The members 67 and 68 are preferably provided with the removable pins 71 and 72 which prevent the members 67 and 68 from being entirely removed from the device. The caster wheels engage the floor or other surface upon which the abrading disc is acting and not only act as rolling supports, but may also be used to tilt the device so as to adjust or vary the portion of the abrading disc which engages the surface along which the device is moved.

In the use of the device, the motors are set in operation and the operator grasps the handles 59 and 60 and moves the rotating abrading disc along the surface to be acted upon. The fan 35 then causes the material removed from the surface the disc is acting upon to be drawn into the inlet 43, chamber 42 and fan chamber 34 and discharged into the collector 40. The fixed part 13 on the section 1 engages the baseboard or any other similar part when the device is brought close to it, so as to prevent the disc from marring the baseboard. The parts are arranged, however, so that the disc can get up to the baseboard so as to act upon the surface all the way up to the baseboard. When the device is being used the usual flexible connection from a wall socket is connected with the member 73 attached to the cover 49.

I claim:

1. An abrading device comprising an abrading disc, a driving motor therefor, a fan, a driving motor therefor, a supporting device for said parts consisting of a lower section and an upper section, removably connected together, said abrading disc mounted in the lower section, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in the upper section in which said fan is mounted, a housing for the fan motor removably connected with the upper section, the fan motor and its housing projecting above the upper section, a connection

leading from the fan chamber to a point in proximity to the edge of the abrading disc.

2. An abrading device comprising an abrading disc, a driving motor therefor, a fan, a driving motor therefor, a supporting device for said parts consisting of a lower section and an upper section, removably connected together, said abrading disc mounted in the lower section, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in the upper section in which said fan is mounted, a housing for the fan motor removably connected with the upper section, the fan motor and its housing projecting above the upper section, a connection leading from the fan chamber to a point in proximity to the edge of the abrading disc, and a cover for covering the motor housings, said cover removably connected with the upper section.

3. An abrading device comprising an abrading disc, a driving motor therefor, a fan, a driving motor therefor, a supporting device for said parts consisting of a lower section and an upper section removably connected together, said abrading disc mounted in the lower section, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in the upper section in which said fan is mounted, a housing for the fan motor removably connected with the upper section, the fan motor and its housing projecting above the upper section, a connection leading from the fan chamber to a point in proximity to the edge of the abrading disc, said upper section being provided with laterally projecting parts, and a wheel adjustably connected with each of said laterally projecting parts, said wheels engaging the surface along which the abrading disc is moved.

4. An abrading device comprising an abrading disc, a driving motor therefor, a fan, a driving motor therefor, a supporting device for said parts consisting of a lower section and an upper section removably connected together, said abrading disc mounted in the lower section, two downwardly projecting separated walls on said lower section beyond the edge of the abrading disc, forming a groove for the passage of material removed by the abrading disc, means for admitting this material into said groove, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in the upper section in which said fan is mounted, a housing for the fan motor removably connected with the upper section, the fan motor and its housing projecting above the upper section, and a connection leading from said fan chamber and connected with said groove.

5. An abrading device comprising an abrading

disc, a driving motor therefor, a supporting device for said parts consisting of a lower section and an upper section removably connected together, said abrading disc mounted in the lower section, a shaft for the abrading disc extending into the upper section, said upper section having an upper wall provided with a recess, a bearing for the abrading disc shaft mounted in said recess, said abrading disc motor being mounted on the upper section and having a shaft extending through an opening therein, the upper wall of the upper section being provided with a second recess, a bearing for said motor mounted in said second recess, a driving connection between said motor shaft and said abrading disc shaft, a fan chamber in said upper section opposite the part of the abrading disc motor which projects into said upper section, a fan in said fan chamber, a motor for driving the fan, and a connection leading from the fan chamber into the lower section and to a point in proximity to the edge of said abrading disc.

6. An abrading device comprising an abrading disc, a driving motor therefor, a fan, a driving motor therefor, a supporting device for said parts consisting of a lower section and an upper section removably connected together, said abrading disc mounted in the lower section, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in the upper section in which said fan is mounted, a housing for the fan motor removably connected with the upper section, the fan motor and its housing projecting above the upper section, a connection leading from the fan chamber to a point in proximity to the edge of the abrading disc, a cover for covering the motor housings, said cover removably connected with the upper section, an electric switch removably connected with said cover, to which the electric motors are electrically connected, and an actuating member connected with said switch and projecting to the exterior of the cover.

7. An abrading device comprising an abrading disc, a driving motor therefor, a fan, a driving motor therefor, a supporting device for said parts consisting of a lower section and an upper section removably connected together, said abrading disc mounted in the lower section, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in the upper section in which said fan is mounted, a housing for the fan motor removably connected with the upper section, the fan motor and its housing projecting above the upper section, a connection leading from the fan chamber to a point in proximity to the edge of the abrading disc, a cover for covering the motor housings, said cover removably connected with the upper section, and two separated handles connected together, said handles removably connected with the top of said cover.

8. An abrading device comprising an abrading

disc, a driving motor therefor, a fan, a driving motor therefor, a supporting device for said parts consisting of a lower section and an upper section removably connected together, said abrading disc mounted in the lower section, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in which said fan is mounted, a housing for the fan motor removably connected with the upper section, the fan motor and its housing projecting above the upper section, and a connection leading from the fan chamber to a point in proximity to the edge of the abrading disc.

9. An abrading device comprising an abrading disc, a driving motor therefor, a fan, a driving motor therefor, a supporting device for said parts consisting of a lower section and an upper sec-

tion removably connected together, said abrading disc mounted in the lower section, a shaft for the abrading disc extending into the upper section, a motor housing for the abrading disc motor, the abrading disc motor and its housing projecting upwardly from the top of the upper section, the motor housing being removably connected with said upper section, said motor having a shaft operatively connected with the shaft of the abrading disc, a fan chamber in the upper section in which said fan is mounted, a housing for the fan motor removably connected with the upper section, the fan motor and its housing projecting above the upper section, a connection leading from the fan chamber to a point in proximity to the edge of the abrading disc, and two wheels, one on each side of the device and supported at points intermediate the front and rear of the supporting structure, said wheels engaging the surface along which the abrading disc is moved.

ARTHUR C. BURLEIGH.
